US0D1090182S

(12) United States Design Patent (10) Patent No.: US D1,090,182 S
(45) Date of Patent: * Aug. 26, 2025

(54) DRINKING GLASS

(71) Applicant: TURKIYE SISE VE CAM FABRIKALARI ANONIM SIRKETI, Istanbul (TR)

(72) Inventor: Umut Sinan Karaca, Istanbul (TR)

(73) Assignee: TURKIYE SISE VE CAM FABRIKALARI ANONIM SIRKETI, Istanbul (TR)

() Term: 15 Years

(21) Appl. No.: 35/520,162

(22) Filed: Dec. 24, 2023

(80) Hague Agreement Data

Int. Filing Date: Dec. 24, 2023

Int. Reg. No.: DM/235313

Int. Reg. Date: Dec. 24, 2023

Int. Reg. Pub. Date: Mar. 1, 2024

(30) Foreign Application Priority Data

Jul. 4, 2023 (TR) 2023/006522

(51) LOC (15) Cl. 07-01

(52) U.S. Cl.

USPC D7/527; D7/531

(58) Field of Classification Search

USPC D7/509-511, 522-524, 527, 528, 532, D7/533, 537, 602, 396.2, 392.1, 396.1, D7/396.6, 531; D3/202

CPC A63F 2009/0058; A47G 19/2205; A47J 41/00; B65D 21/02

See application file for complete search history.

(57) CLAIM

The ornamental design for a drinking glass as shown and described.

DESCRIPTION

1. Drinking glass
2. Drinking glass
3. Drinking glass
4. Drinking glass
5. Drinking glass
7. Drinking glass
- 1 : Perspective
- 2 : Perspective
- 3 : Perspective
- 4 : Perspective
- 5 : Perspective
- 7 : Perspective

The portions of the drinking glass shown in broken line form no part of the claimed design. The dot-dash broken lines depict the bounds of the claim and form no part thereof.

1 Claim, 6 Drawing Sheets

US D1,090,182 S
